UNITED STATES PATENT OFFICE.

CHARLES FISHER HYDE, OF CHICAGO, ILLINOIS.

MEDICINE-DROPPER.

1,055,180.

Specification of Letters Patent.

Patented Mar. 4, 1913.

Application filed May 14, 1912. Serial No. 697,227.

To all whom it may concern:

Be it known that I, CHARLES F. HYDE, a citizen of the United States, and a resident of Chicago, in the county of Cook and State 5 of Illinois, have invented a new and Improved Medicine-Dropper, of which the following is a full, clear, and exact description.

This invention relates to droppers for 10 liquids, and especially to bottles adapted to contain medicines from which the same may be dropped easily and accurately.

The object of the invention is to provide a bottle of the special nature indicated 15 which is more effective for its purpose than those commonly employed and which will be substantially airtight when not in use as a dropper so that the contents of the bottle will be properly preserved.

20 The invention consists in the construction and combination of parts to be more fully described hereinafter and particularly set forth in the claim.

Reference is to be had to the accompanying 25 drawings forming a part of this specification in which like characters of reference indicate corresponding parts in all the views, and in which—

Figure 1 is a vertical face view of the 30 bottle made in accordance with a preferred embodiment of this invention; Fig. 2 is a vertical section through the neck of the bottle substantially on the line 2—2 of Fig. 1; and Fig. 3 is a similar view with the movable parts in a different position.

Referring particularly to the drawings, I have shown at 10 any suitable form or size 40 of a container for liquids, hereinafter referred to as a bottle, but which obviously may be a jug or some other specific type of container. Said bottle is shown provided with a neck 11 adapted to be closed by a cork 12 in the usual manner.

The interior surface of the neck 11, adjacent the mouth, is formed with a longitudinal groove 13 through which, when the bottle is tilted, the medicine may be caused or permitted to flow in drops. To permit this action the stopper may be withdrawn 50 slightly if it had been previously forced so

deeply into the neck as to make the bottle air-tight. To facilitate the flow of the liquid through the groove 13, the stopper 12 may be formed with a companion groove 14 which may be caused to register with the 55 bottle groove as indicated in Fig. 2. Whether or not the stopper must be specially formed as indicated will, of course, depend upon the viscosity of the liquid or the rate at which it is to be delivered from the bottle. 60

On the side of the neck 11 opposite the groove 13 is formed an external longitudinal rib 15 which merges into the rim 16 surrounding the mouth of the bottle. Said rib 15 serves to reinforce the bottle neck and 65 to provide a substantial base for a comparatively long inclined vent 17 extending entirely through the wall of the neck, the inclination of said vent being down toward the inside of the bottle. The purpose of this 70 vent 17 is to admit air during the operation of dropping medicine or the like from the bottle through the groove 13, as described above. When the bottle is not used as a dropper, I prefer to seal the vent 17 by 75 means of a flat elastic band 18 surrounding the neck of the bottle and adapted to slip over the outer end of said vent, as shown in Fig. 3, the band, however, being adapted to be slipped up or down so as to open the vent 80 as may be required. When the band is moved away from the vent, the admission of air may be controlled more or less, as desired, by the operator's thumb or finger, the form of the neck with respect to the rib 85 facilitating such action of the operator.

I wish it to be understood that I am not to be limited to any particular materials, or relative sizes and proportions of the parts or features of this invention, reserving the 90 right to vary from those shown to a considerable extent without departing from the spirit of the invention.

Having thus described my invention, what I claim as new and desire to secure by Letters Patent is:

In a medicine dropper, the combination with a bottle having a neck provided with a longitudinal groove along its inner surface adjacent the mouth, a longitudinal rib 100

on the outside of the neck opposite said groove, and a downwardly and inwardly inclined vent extending through said rib and neck, of means slideable up and down on the
5 neck and rib to seal said vent, substantially as set forth.

In testimony whereof I have signed my

name to this specification in the presence of two subscribing witnesses.

CHARLES FISHER HYDE.
